DESIGN FOR A CONTROL DEVICE FOR PHONOGRAPHS

Ray Patten, Bridgeport, Conn., assignor to Dictaphone Corporation, New York, N. Y., a corporation of New York

Application February 25, 1937, Serial No. 67,848

Term of patent 14 years

To all whom it may concern:

Be it known that I, Ray Patten, a citizen of the United States and a resident of the city of Bridgeport, county of Fairfield, and State of Connecticut, have invented a new, original, and ornamental Design for a Control Device for Phonographs, of which the following is a specification, reference being had to the accompanying drawing, forming part thereof.

The figure is a perspective view of a control

device for phonographs, showing my new design.

The two sides of the control device casing which are not shown in the drawing are like the two sides which are shown, except for the absence of slots for the pedals; and the bottom beading goes all the way around the structure.

I claim:

The ornamental design for a control device for phonographs, as shown and described.

RAY PATTEN,
